UNITED STATES PATENT OFFICE.

ANDREW J. SORENSEN, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

DECODING APPARATUS.

Application filed November 18, 1926. Serial No. 149,257.

My invention relates to decoding apparatus.

I will describe one form of apparatus embodying my invention, and will then 5 point out the novel features thereof in claims.

In the accompanying drawings Fig. 1 is a fragmental view, partly diagrammatic showing one form of apparatus embodying my 10 invention. Fig. 2 is a top view of a portion of the apparatus shown in Fig. 1. Fig. 3 is a detail view of a portion of the contact mechanism for use with the apparatus shown in Fig. 1. Fig. 4 is a diagrammatic view 15 of one form of governing means suitable for co-operation with the apparatus shown in the preceding figures. Fig. 5 is a chart illustrating the position of certain parts of my apparatus under various operating conditions. 20

Similar reference characters refer to similar parts in each of the several views.

Referring first to Fig. 1, the reference character F designates a relay which may be 25 supplied with current in any suitable manner in the form of code impulse combinations consisting of short impulses of current separated by time intervals. As shown in Fig. 5 code number one consists of groups 30 composed of single impulses separated by time intervals. Code number two consists of groups of two impulses each, the impulses being separated by short intervals and the groups by longer intervals. Codes three 35 and four consist of groups of three and four impulses respectively, and spaced as in code number two. For the purposes of this specification I will assume that the length of each impulse and of the intervals between impulses in a group is one-fourth of a second, and that the length of the intervals between 40 groups of impulses is one second.

The relay F has a contact 13 which controls the circuits for two parallel connected magnets M and M¹. These magnets are at times supplied with current from a suitable source, here shown as a generator G, and are arranged to operate a selector comprising a pivoted contact controlling lever 15 which 45 is provided at its lower end with a plurality of teeth 19. This lever is fastened on a sleeve 15¹ (see Fig. 2) and is free to rotate in a clockwise direction about a fixed shaft 14. Also mounted on the shaft by means

of a sleeve 16¹ is a driving segment 16 provided with two sets of teeth 17 and 18. In its normal position the segment 16 abuts a stop E as shown in the drawing. When current impulses are being supplied to the relay F the segment 16 is rotated in a clockwise direction by means of the magnet M. This magnet consists of a yoke 20, a core 21 carrying a winding 22, and an armature 23. The armature 23 is attracted whenever the magnet is energized and causes a driving 55 pawl 24 to engage one of the teeth 17 thereby rotating the segment 16 through a predetermined distance. The driving pawl 24 is pivotally secured at 25 to the armature 23 so that when the armature 23 is released 60 the pawl may rotate upwardly about the pivot 25 and escape the teeth 17 on the segment 16. The segment 16 normally engages a pin P¹ which is secured at one end 65 to an arcuate arm 26 and at the other end to a similar arm 28 (see Fig. 2). When the segment 16 moves, it acts through the pin P¹ to swing arm 26 in a clockwise direction, and when the magnet M is de-energized a latch 29 which is secured to the armature 23 engages one of the teeth 27 on the arm 26 so that this arm can be held in an advanced position. The member 28 carries a second pin P² which is rigidly secured thereto in such position that when the segment 16 has been rotated by a single impulse 70 being supplied to the magnet M, the pin will just engage the lever 15 but will not rotate it in a clockwise direction unless the segment 16 receives two or more impulses 75 in succession.

In order to prevent the lever 15 from returning to its initial position between separate impulses of a code impulse combination, I provide the second magnet M¹. This 80 magnet has a smaller air gap than the magnet M and therefore attracts its armature 23 more quickly than does magnet M so that when a code impulse is supplied to the relay F the magnet M¹ will lift its armature 85 before magnet M lifts its armature. The magnet M¹ is also made slow-releasing by means of a closed conducting sleeve 21^a, so that it will hold its armature up between 90 impulses in a group but will not bridge the interval between separate groups. The armature 23 of magnet M¹ carries two latches 30 and 31, and in its de-energized 95

position it engages a stop B. The latch 30 is adapted to engage teeth 19 on the lever 15 whenever magnet M¹ is energized. In a similar manner the latch 31 engages teeth 18 on the driving segment 16. It will now be clear that when code number two consisting of two impulses in a group is supplied to relay F, the segment 16 will be advanced twice by the two successive engagements of the pawl 24 with the first and second teeth, respectively, of a segment. When the first impulse is supplied to the magnet M the segment 16 will be rotated, and at the same time energization of the magnet M¹ will cause the latches 30 and 31 to engage the members 15 and 16 respectively. This impulse causes the pin P² to engage the lever 15, but the lever is not advanced until the second impulse is supplied to the magnet M. During the interval between the two impulses the latch 31 will engage the second tooth 18 on the segment 16 and will prevent the segment from returning to its zero position against the stop E, and will bridge the one-fourth second interval so that when the second impulse is supplied to the magnet M the pawl 24 will engage the second tooth 17 on the segment 16 and will therefore rotate the segment until the latch 31 engages the third tooth 18 of this segment and latch 30 engages the second tooth 19 on the lever 15. When the magnet M is de-energized following the receipt of the second impulse the latch 29 will engage the third tooth 27 of the arm 26 so as to hold the lever 15 in its advanced position when the magnet M is de-energized.

The manner in which the contacts are controlled by the lever 15 will be understood from the illustration in Fig. 3. Referring now to this view the lever 15 has a portion 32 (see also Fig. 2) which is bent over at right angles to the lever and carries thereon a contact supporting member 33 of insulating material which is secured to the lever by suitable fastening means 73. The member 33 carries two flexible contact fingers 34 and 35 and two rigid contact fingers 36 and 37. Contact finger 34 carries two contact-points 38 and 40 which are arranged to co-operate with other contact-points 39 and 41, respectively, 38 and 39 being designated generally by reference character L¹, and 40 and 41 by K¹. Contact-point 39 is secured to a fixed support 42, this support being fastened to a portion of the frame of the device which has been omitted from the drawing for the sake of simplicity. The contact-point 41 is secured to the rigid contact finger 36. In a similar manner the contact finger 35 carries two contact-points 43 and 44 which are adapted to co-operate, respectively, with a contact-point 44 on the finger 37 and a contact-point 45 which is secured to the frame of the machine by means of a

member 46; 43 and 44 being designated generally by K², and 44 and 45 by L². When the lever 15 occupies its normal position as shown in Figs. 1 and 3 contact L¹ is closed, but when the member 15 is rotated in clockwise direction far enough to open contact L¹ the resiliency of the finger 34 will cause contact K¹ to close. When code number one consisting of one impulse in each group is supplied to the relay F the contact L¹ remains closed because the lever 15 is not moved from its initial position. Whenever code impulse combinations consisting of groups of two or more impulses are supplied to the magnet M, the contact L² is opened and the contact K¹ is closed, the contact K² remaining closed until the lever 15 has rotated far enough to cause contact L² to close, thereby opening the contact K². The lever 15 is biased to the position shown in the drawing by means of a counter-weight W which causes contact L¹ to be closed when this lever is not held by the pin P² or by latch 30.

For the purpose of controlling other contacts I provide a contact supporting member 47 composed of insulating material and pivotally mounted on the shaft 14. The member 47 is biased to the position shown, by means of a counter-weight Z, and carries a flexible contact finger 48 and a rigid contact finger 49. The finger 48 carries two contact-points 50 and 53 which are adapted to co-operate with two contact-points 51 and 54, respectively, to form contacts L² and K², respectively. The contact-point 51 is secured to a support 52 on the frame of the machine, while the contact-point 54 is secured to the rigid contact finger 49. Whenever code impulse combinations consisting of groups of three or more impulses are supplied to the magnet M the lever 15 is rotated far enough to cause a projecting arm 53 on the contact supporting member 33 to engage the member 47 and rotate it in a clockwise direction. When the member 47 is rotated through a slight angle the contact L² is opened and due to the resiliency of contact finger 48 the contact-points 53 and 54 engage to close the contact K². It will now be clear that when code number one is supplied to relay F the contacts L¹, L² and K² are closed, when code number two is supplied contacts K¹, L² and K³ are closed, when number three is supplied to the relay F, contacts K¹, K² and K³ are closed, and that when code number four is supplied, contacts K¹, K² and L² are closed. The operation of these contacts is set forth in detail in Fig. 5.

Referring now to Fig. 4 the armature of magnet M operates a contact bar 58 which controls two slow-release relays R¹ and R². When the magnet is energized, the relay R² is energized over a circuit from a suitable source of current, here shown as a generator 130

G, through wires 54 and 55, winding of relay R², wire 56, contact 57—58 and wire 59 back to the negative terminal of the generator.

- When the magnet M is deenergized the relay R¹ is energized over a circuit from the generator G through wires 54 and 55, winding of relay R¹, wire 60, contact 61—58 of magnet M and wire 59 back to the generator. The relays R¹ and R² are made slow-releasing so that they are capable of holding their contacts closed between the separate groups of impulses, that is, they are capable of holding their contacts closed for a period slightly more than one second, therefore, when code impulse combinations are being supplied to the relay F so that magnet M is being periodically energized and de-energized, the relays R¹ and R² will constantly hold their front contacts 62 and 64, respectively, in closed position. If current is being continuously supplied to the relay F so that the magnet M is constantly energized, the relay R² will hold its front contact 64 closed and relay R¹ will be deenergized. Under this condition a lamp S^a will be energized over a circuit from the positive terminal of the generator G through wire 54, lamp S^a, back contact 63 of relay R¹ and wire 67 to the negative terminal of the generator. When no current is being supplied to the relay F so that the magnet M remains de-energized, the relay R¹ is continuously energized, but relay R² is de-energized, and so a lamp S^b is lighted over a circuit from the positive terminal of the generator G, through wire 54, lamp S^b, back contact 65 of relay R², wire 68, front contact 62 of relay R¹ and wire 67 to the negative terminal of the generator. The relays R¹ and R² co-operate with the contacts operated by the lever 15 to control four lamps S¹, S², S³ and S⁴, respectively. The exponent applied to the reference character for each lamp corresponds to the numeral of the code given in Fig. 5, which must be supplied to the relay F to light the lamp. For example, when code one is supplied to the relay F, lamp S¹ is lighted. The circuit for the lamp S¹ under these conditions is from the positive terminal of the generator G through wires 54 and 69, lamp S¹, contact L¹, contact finger 34, wire 70, contact L², contact finger 35, wire 71, front contact 64 of relay R², wire 68, front contact 62 of relay R¹ and wire 67 back to the negative terminal of the generator. When code two is supplied to the relay F contacts K¹, L² and K³ are closed so that the lamp S² is lighted over a circuit which will be obvious from the drawing. Similarly when code three is supplied to the relay F, contacts K¹, K², and K³ are closed so that the lamp S³ is lighted. When code four is supplied to the relay F the contacts K¹, K² and L³ are closed so that the lamp S⁴ is lighted. It will now be clear that by se-

lecting the desired code which is to supply current to the relay F any one of the lamps S¹, S² etc., may be lighted.

In describing the operation of the apparatus I will assume that code number one is being supplied to the relay F. With the parts in the positions shown in the drawing the segment 16 occupies its zero position engaging the stop E. The lever 15 occupies such position that the contact L¹ is closed, and is held in this position by the counter-weight W, and the arm 26 occupies a position in which the latch 29 on armature 23 of magnet M engages the first notch 27 of this arm. The contact L¹ prevents the lever 15 from being moved in a counter-clockwise direction. The pin P¹ in the arm 26 engages the segment 16 and the magnet M is de-energized so that the relay R¹ is energized and lamp S^b is lighted. The first impulse of code number one supplied to relay F will energize this relay causing it to close its front contact and thereby completing a circuit for the magnets M and M¹. When these magnets are energized the armature 23 of magnet M¹ will be raised first, bringing latches 30 and 31 into contact with the teeth of lever 15 and segment 16, respectively. Immediately after the energization of magnet M¹ the armature 23 of magnet M will be raised, causing the pawl 24 to engage the first tooth 17 of the segment 16 and so to rotate the segment a short distance. Since the pin P¹ is in engagement with this segment, the arm 26 will also be rotated and will be held in its advanced position by latch 29 engaging the second tooth 27 of the arm 26 when magnet M becomes de-energized. During the time in which magnet M is dropping its armature 23 to lock the arm 26 in its advanced position, the magnet M¹ holds its armature 23 up because this magnet is slow-releasing, and so the latch 31 will be held in engagement with the second tooth 18 of segment 16 until the latch 29 engages the arm 26. After slightly more than one-fourth of a second has elapsed the armature 23 of magnet M¹ will be released, latch 31 will release segment 16 and this segment will return to zero position under the influence of gravity, the arm 26 being held in its advanced position by the latch 29. When one second has elapsed another impulse will be supplied to the relay F and the sequence of operations just described will be repeated. The alternate energization and de-energization of magnet M by the impulses of code number one will operate the contacts 57—58 and 61—58 so that relays R¹ and R² will hold their front contacts 62 and 64, respectively, closed as long as this code is supplied to relay F. Contacts L¹ and L² will both be closed so that lamp S¹ will remain lighted. I will next assume that code number two is supplied to the relay F. When the first

impulse is supplied to the relay, the magnet M becomes energized and pawl 24 on armature 23 engages the first tooth 17 of the segment 16 and rotates this segment through a small angle, the segment being prevented from returning to its initial position by the latch 31 engaging the second tooth 18 of the segment. When armature 23 releases, the latch 29 engages the second tooth 27 on the arm 26 so that this arm is held in its advanced position. When the second impulse of the group is supplied to the magnet M the pawl 24 engages the second tooth 17 of the segment 16 and again rotates this segment until the latch 31 engages the third tooth 18 of the segment and the latch 30 engages the second tooth 19 of lever 15, the lever 15 having been moved from its initial position during the second impulse of the group by the engagement of the pin P² with this lever. During the one second interval following the first group, the armature 23 of magnet M is released and latch 29 engages the third tooth on arm 26 holding this arm in its advanced position. The magnet M¹ holds its armature 23 sufficiently long to prevent the lever 15 from returning to its initial position before the latch 29 engages the arm 26.

As soon as magnets M and M¹ release their armatures, the segment 16 returns to its initial position against the stop E. At the end of the one second interval the first impulse of the next group causes magnets M and M¹ to pick up and latch 30 engages the second tooth 19 on lever 15, preventing this lever from dropping back when latch 29 releases arm 26. Segment 16 is again advanced two steps, and latch 31 prevents it from returning between the impulses. Latch 30 holds the lever 15 in its advance position when latch 29 is released by energization of magnet M and so the contacts operated by lever 15 do not change their position during either the long or the short intervals in the code. As long as this code is supplied to the relay, the lever 15 will occupy its first advanced position in which the contact L¹ is opened and the contact K¹ is closed. Contact L² is also closed, and so the lamp S² is lighted.

When the relay F receives code number three consisting of groups of three impulses, the operation of the apparatus will be similar to the operation just described in connection with code number two, with the exception that with the three impulses the segment 16 will be advanced three time so that the latch 29 controlled by magnet M will engage the fourth tooth 27 on arm 26 and will hold the lever 15 in such position that contacts K¹, K², and K³ are closed lighting the lamp S³.

If code number four is supplied to the relay F the segment 16 is advanced four

times so that at the end of one group of impulses the latch 29 engages the fifth tooth 27 of arm 26 and the lever 15 is held in such position that contacts K¹, K² and L³ are closed. With these contacts closed the lamp S³ will be lighted.

It will be understood that if in changing from one code to another the first group of impulses in the new code follows the last group of impulses in the old code without a time interval of one second, the segment 16 will be advanced according to the number of impulses which magnet M receives, but at the end of the group it will return to its position against stop E and on the next series of impulses will be advanced the proper distance so that lever 15 will take its position according to the new code. My arrangement therefore insures that a proper indication will be given in accordance with the code supplied to the relay.

The apparatus herein described is suitable for, though in no way limited to, use in automatic train control systems in which train carried governing means is controlled by current impulses received from the trackway. In systems of this character current supplied to the track rails in the form of code impulse combinations, as shown in Fig. 5, is picked up by apparatus on the train, and is supplied to decoding apparatus arranged to control governing means in any suitable manner.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a relay at times supplied with different code impulse combinations, a selector associated with said relay comprising a first movable member biased to a normal position, a second and a third movable members, means for advancing the first member from its normal position for each impulse supplied to the relay, means for holding the first member in its advanced position between successive impulses in a combination but releasing it between combinations, means whereby the second member always follows the advance movements of the first member and also follows its return movements unless restrained, means for restraining the second member in its advanced position between impulse combinations but releasing it during the impulses of a combination, means whereby the third member always follows the advance movements of the second member and also follows its return movements unless restrained, means for restraining the third member in its advanced position during the same

periods as the first member, a plurality of contacts variably controlled by the different positions of the third member, and governing means controlled by said contacts.

- 5 2. In combination, a relay at times supplied with different code impulse combinations, a selector associated with said relay comprising a first movable member biased to a normal position, a second and a third 70
10 movable members, means for advancing the first member from its normal position for each impulse supplied to the relay, means for holding the first member in its advanced position between successive impulses in a combination but releasing it between combinations, means whereby the second member always follows the advance movements of the first member and also follows its return movements unless restrained, means for 75
15 restraining the second member in its advanced position between impulse combinations but releasing it during the impulses of a combination, means whereby the third member always follows the advance movements of the second member and also follows its return movements unless restrained, means for 80
20 restraining the third member in its advanced position during the same periods as the first member, and governing means controlled by said third member. 85
3. In combination, a relay at times supplied with different code impulse combinations, a selector associated with said relay comprising a first movable member biased to a normal position, a second and a third 90
25 movable members, means for advancing the first member from its normal position for each impulse supplied to the selector, means for holding the first member in its advanced position between successive impulses in a combination but releasing it between combinations, means whereby the second member always follows the advance movements of the first member and also follows its return movements unless restrained, means for restraining the third member in its advanced position during the same periods as the first member, and governing 95
30 means controlled by said third member. 100
- 35 4. In combination, a relay at times supplied with different code impulse combinations, a selector associated with said relay comprising a first movable member biased to a normal position, a second and a third movable members, means for advancing the first member from its normal position for each impulse supplied to the relay, means for holding the first member in its advanced position between successive impulses in a combination but releasing it between combinations, means whereby the second member always follows the advance movements of the first member and also follows its return movements unless restrained, means for restraining the second member in its advanced position between impulse combinations but releasing it during the impulses of a combination, means whereby the third member always follows the advance movements of the second member and also follows its return movements unless restrained, means for restraining the third member in its advanced position during the same periods as the first member, a plurality 105
40 of contacts variably controlled by the different positions of said third member, and governing means controlled by said contacts. 110
- 45 5. In combination, a selector supplied at times with different code impulse combinations and comprising a first movable member biased to a normal position, a second and a third movable members, means for advancing the first member from its normal position for each impulse supplied to the selector, means for holding the first member in its advanced position between successive impulses in a combination but releasing it between combinations, means whereby the second member always follows the advance movements of the first member and also follows its return movements unless restrained, means for restraining the second member in its advanced position between impulse combinations but releasing it during the impulses of a combination, means whereby the third member always follows the advance 115
50 movements of the first member and also follows its return movements unless restrained, means for restraining the third member in its advanced position during the same periods as the first member, a pair of slow release relays controlled by said means for advancing the first member, and governing means controlled jointly by said third member and said slow release relays. 120
- 55 6. In combination, a selector supplied at times with different code impulse combinations and comprising a first movable member biased to a normal position, a second and a third movable members, means for advancing the first member from its normal position for each impulse supplied to the selector, means for holding the first member in its advanced position between successive impulses in a combination but releasing it between combinations, means whereby the second member always follows the advance movements of the first member and also follows its return movements unless restrained, means for restraining the second member in its advanced position between impulse combinations but releasing it during the impulses of a combination, means whereby the third 125
60 member always follows the advance movements of the first member and also follows its return movements unless restrained, means for restraining the second member in its advanced position between impulse combinations but releasing it during the impulses of a combination, means whereby the third 130
65 member follows the advance movements of the second member and also follows its return movements unless restrained, means for restraining the third member in its advanced position during the same periods as the first member. 135

member always follows the advance movements of the second member and also follows its return movements unless restrained, means for restraining the third member in 5 its advanced position during the same periods as the first member, a pair of slow release relays controlled by said means for advancing the first member, and governing means controlled jointly by said third member and the slow release relays.

7. In combination, a selector comprising a quick-releasing magnet and a slow-releasing magnet, which magnets are at times supplied with impulse combinations, a first movable 15 member biased to a normal position, a second and a third movable members, means controlled by said quick-releasing magnet for advancing the first member from its normal position for each impulse supplied to the 20 selector, means controlled by said slow-releasing magnet for holding the first mem-

ber in its advanced position between successive impulses in a combination but releasing it between combinations, means whereby the second member always follows 25 the advance movements of the first member and also follows its return movements unless restrained, means for restraining the second member in its advanced position between impulse combinations but releasing it 30 during the impulses of a combination, means whereby the third member always follows the advance movements of the second member and also follows its return movements unless restrained, means controlled by 35 said slow-releasing magnet for restraining the third member in its advanced position during the same periods as the first member, and governing means controlled by said 40 third member.

In testimony whereof I affix my signature.
ANDREW J. SORENSEN.
